(57) **CLAIM**

The ornamental design for an armrest for airplane pilot, as shown and described.

DESCRIPTION

FIG. 1 is an exploded view of the armrest for airplane pilot.

FIG. 2 is a top view thereof.

FIG. 3 is a bottom view thereof.

FIG. 4 is a rear view thereof.

FIG. 5 is a front view thereof.

FIG. 6 is a first side thereof; and,

FIG. 7 is second side view thereof.

The broken lines of FIGS. 1-7 are included for the purpose of illustrating environmental structure and form no part of the claimed design.
